UNITED STATES PATENT OFFICE.

PAUL D. BUNKER, OF FORT HANCOCK, NEW JERSEY.

TRACER FOR PROJECTILES.

1,080,413.

Specification of Letters Patent.

Patented Dec. 2, 1913.

Application filed April 30, 1913. Serial No. 764,657.

To all whom it may concern:

Be it known that I, PAUL D. BUNKER, a citizen of the United States, residing at Fort Hancock, in the county of Monmouth and State of New Jersey, have invented certain new and useful Improvements in Tracers for Projectiles; and I do hereby declare the following to be a full, clear, and exact description of the invention, such as will 10 enable others skilled in the art to which it appertains to make and use the same.

The present invention relates to projectiles and more especially to tracers therefor, and it has for its purpose to provide a means whereby the trajectory of the projectile may 15 be visibly indicated to the end of determining any inaccuracy in the estimated range for firing.

The invention has for its further purpose 20 to provide a device of this character which forms an attachment to, and is carried on the exterior of the projectile, and which is of such construction and so located as to not offer additional resistance to that normally 25 encountered by the projectile in flight.

With these and other objects in view the invention consists in the novel details of construction and combinations of parts more 30 fully hereinafter disclosed and particularly pointed out in the claims.

The invention is shown by way of illustration in the accompanying drawing wherein—

1 indicates the projectile shown herein as 35 being of the explosive type and having the usual rotating band 2, and base 3 designed to be fitted with a fuse at 4.

The tracer consists of a cap or casing 5 providing, a chamber 6 for holding a combustible of a smoke producing or illuminating pyrotechnic substance. The casing 5 is of reducing or parabolic design in cross section, and is constructed at its apex X to be fitted with a fuse and provide an opening 40 for the emission of the combustible. The casing is secured to the projectile 1 at the base 7 thereof preferably through the medium of a ring or collar 8 which fits on the reduced portion 9 of the casing, and has its 45 exterior surface 10 of the same contour as that of the casing 5.

The collar or ring is secured on the casing 5 by shrinkage or in any other suitable manner, and a pin 11 passes through said collar and engages with the casing as in the 55 manner shown. The base 7 of the projectile has screw threads 12 for engaging with the screw threads 13 formed on the collar, and a thin metal ring or band 14 is interposed between the collar and the base of the projectile. 60

It is obvious that those skilled in the art may vary the details of construction, method of attachment to the projectile, and arrangement of parts without departing from 65 the spirit of my invention, and therefore I do not wish to be limited to such features except as may be required by the claims.

I claim:

1. The combination with a projectile, of 70 a tracer therefor comprising a casing carried wholly on the exterior of the projectile and adapted to hold a combustible, the exterior surface of said casing conforming with the exterior surface of the projectile. 75

2. The combination with a projectile, of 80 a tracer therefor comprising a casing mounted on the base of the projectile and wholly exterior thereof and adapted to hold a combustible, the exterior surface of said casing 85 conforming with the exterior surface of the projectile.

3. The combination with a projectile, of 90 a tracer therefor comprising a casing mounted wholly exterior of and on the base of the 85 projectile and of decreasing cross section therefrom, and adapted to hold a combustible, the exterior surface of said casing conforming with the exterior surface of the projectile.

4. The combination with a projectile, of 95 a tracer therefor comprising a casing mounted on the base of the projectile and exterior thereof, and of substantially parabolic design in longitudinal cross section.

5. The combination with a projectile, of 100 a tracer therefor comprising a casing adapted to hold a combustible; and a ring detachably connecting the casing to the base of the projectile, and lying flush with the exterior surfaces of said casing and the projectile.

6. The combination with a projectile, of a tracer therefor comprising a casing adapted to hold a combustible; and a ring carried by said casing and having screw connection with the base of the projectile.

7. The combination with a projectile, of a tracer therefor comprising a casing of parabolic design detachably mounted on the

base of the projectile, and having the apex thereof constructed to be fitted with a fuse. 10

In testimony whereof, I affix my signature, in presence of two witnesses.

PAUL D. BUNKER.
